BUCKET HANGER

Vallie A. Thomas, Washington, D. C.

Application October 6, 1944, Serial No. 557,460

4 Claims. (Cl. 248—212)

This invention aims to provide a bucket hanger for assembly with a pitcher-pump, the hanger being strong, easily applied, and inexpensive to make, in that a small amount of stock is used.

Within the scope of what is claimed, changes in the embodiment of the invention herein disclosed may be made, without departing from the spirit of the invention.

In the drawing:

Figure 1 shows the hanger in perspective and 10 assembled with a pitcher-pump.

Figure 2 shows the hanger in side elevation and assembled with a pitcher-pump.

The letter P marks a pitcher-pump, including a tubular body 1 having a trough-shaped spout 2, overhung at its inner end by a depending annular flange 3 on a cap 4, carrying pump-operating means 5, the cap being releasably held on the upper end of the body by a set screw 6 or the like.

The bucket hanger forming the subject matter of this application comprises an approximately U-shaped body made of a single piece of stiff material, such as heavy wire, the body comprising side arms 7, the rear portions 8 of which preferably are parallel and extend under the flange 3 of the cap 4, and terminate in rectangularly disposed, upstanding fingers 9, engaged behind the cap-flange to prevent the hanger from slipping forwardly.

The forward portions 10 of the arms 7 converge and merge into a connecting bend 11, said portions of the arms being downwardly convexed as shown at 12, immediately to the rear of the bend, to form an upwardly facing concaved seat 14 for the reception of the bail of a bucket (not shown).

The arms 7 are curved upon themselves to define depending eyes 15 which, cooperating with the inner surfaces of the side walls of the spout 2, aid in limiting lateral shifting of the hanger. In the eyes 15 is fixedly bound a cross piece 16, which forms a strengthening tie between the arms 7. The cross piece 16 supports the hanger, since the end portions of the cross piece extend out-

wardly beyond the arms 7 and rest on the upper edges of the side walls of the spout 2. The eyes 15 connect the rear portions 8 of the arms 7 with the forward portions 10 thereof.

To the rear of the convexity shown at 12 the forward portions 10 of the arms 7 have a less pronounced downward convexity shown at 17 and functioning to stiffen the arms, the better to enable the hanger to withstand the weight of a bucket suspended from the seat.

The hanger is strong, easily applied, and economical of material.

What is claimed:

1. A bucket hanger for use on a pitcher pump, comprising an approximately U-shaped body including side arms and a bend connecting the outer ends of the arms, the inner ends of the arms having upstanding fingers and a cross piece carried by the intermediate portions of the arms and extended outwardly beyond the arms.

2. A bucket hanger for use on a pitcher pump, comprising an approximately U-shaped body, including side arms and a bend connecting the outer ends of the arms, the inner ends of the arms having upstanding fingers, the arms being curved upon themselves, intermediate their ends, to form eyes, and a crosspiece fixedly bound in the eyes, the crosspiece extending outwardly beyond the arms.

3. A bucket hanger for use on a pitcher pump, constructed as set forth in claim 2, and wherein the eyes depend to form stops which, cooperating with the side walls of a pump spout, limit the lateral movement of the hanger thereon.

4. A bucket hanger for use on a pitcher pump, constructed as set forth in claim 2, and wherein the arms are downwardly convexed immediately to the rear of the bend, to define an upwardly facing concaved bail-seat, the arms having a less pronounced downward convexity, extending from the seat to the eyes, and strengthening the hanger to withstand the weight of a bucket suspended from the seat.
